PORTABLE ELEVATOR

Martin M. Haider, St. Paul, Minn., assignor of
one-third to Joseph G. Haider and one-third to
Rudolph Mottl, both of St. Paul, Minn.

Application May 20, 1941, Serial No. 394,353

2 Claims. (Cl. 187—9)

My invention relates to improvements in portable elevators for use more particularly, although not necessarily, in construction work to lift loads of material and workmen to different levels, corresponding to floor levels.

The principal object of the invention is to provide a simply constructed, light-weight, strong apparatus of this character which may readily be moved from place to place, as the case may require, requires no setting up of parts, is easy to load and unload, safe, and easy to operate.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in rear elevation of a preferred embodiment of my invention.

Figure 2 is a view in side elevation.

Figure 3 is a view in front elevation.

Figure 4 is a view in horizontal section taken on the line 4—4 of Figure 3 and drawn to an enlarged scale.

Figure 5 is a view in transverse section of the lift or cage.

Figure 6 is a fragmentary view partly in section and partly in elevation, of the carriage.

Figure 7 is a view in perspective of one of the jacks, and

Figure 8 is a fragmentary view in perspective of one of the lift or cage guides.

Referring to the drawings by numerals, in the illustrated embodiment thereof my improved elevator comprises a carriage 1 having the form of a generally rectangular bed 2 provided with small diameter rollers 3 suitably journaled, as at 4, therein so as to provide a low center of gravity for the bed 2.

The bed 2 is designed to support a superstructure including a rectangular base 5 fitting flat on the bed 2 and from which arise corner uprights 6 defining a generally rectangular skeleton elevator shaft, there being a pair of such uprights 6 at what constitutes the front side of the shaft, and a similar pair at the rear side of said shaft. A pair of vertical reinforcing cleats 7 extend along the inner sides of the front uprights 6. A flat bottom rest 8, for a purpose presently seen, is provided at the bottom of the shaft intermediate the uprights 6. Horizontal tie bars 9 connect the front and rear side uprights at suitable levels. The front side uprights 6 are connected at the

tops thereof by a cross bar 10, and the rear side uprights 6 are similarly connected by the cross bar 11. A frame comprising a pair of standards 12 and a top cross bar 13 arises from opposite sides of the shaft or superstructure and for a purpose presently explained. A sheave 14 is suspended from the top bar 13 centrally thereof by an eye-bolt 15. An idler pulley 16 is suitably mounted on one of the standards 12. A pair of channel guides 17, for a lift or cage presently described, are suitably mounted in the shaft or superstructure in upstanding position centrally of the shaft upon opposite sides thereof. At the front side of the shaft and at substantially the level of the usual second floor of a building above the ground or first floor, a cross beam 18 is provided with its ends suitably secured to the front side uprights 6. The front side of the shaft above the beam 18 is closed against exit from the shaft by a skeleton wall comprising, in the present instance, the cross beam 19 and upright panels 20 extending from the cross beam 19 to the top bar 10.

A stop bail is provided at the top of the shaft comprising a pair of side arms 21, and a cross bar 22, the side arms being pivoted on hooks 23 secured at the top of the shaft at opposite sides thereof, the arrangement being such that the stop bail is swingable upwardly over the top of the shaft proper into a position to limit upward movement of the lift or cage, presently described, when said lift reaches a level corresponding to the level of the usual third floor of a building. The stop bail 22, 21, may be swung downwardly when not in use into a pair of notches 24 provided in the rear pair of uprights 6, whereby said stop bail may be adjusted into an out of the way idle position.

The lift or cage, comprises a flat bottom 25, a pair of side frames 27, and a top cross bar 28, having an eye bolt 29 therein to which is connected one end of the hoisting cable 30 trained over the aforementioned sheave 14 and idler 16 and then downwardly along one side of the shaft to a hoisting drum 31 suitably mounted on the base 5 of the shaft.

A hoisting engine of the internal combustion type designated 32 is mounted on the base 5 at one side of the shaft and operatively connected to the hoisting drum 31 by a clutch 33 adapted to be disengaged by a suitable hand lever 34 against the tension of a suitably arranged spring 35. The numeral 36 designates a fuel supply tank for the engine 32.

Side guides 37 on the lift or cage, and extend-

ing into the aforementioned guide channels 17 guide the lift or cage during elevation and lowering thereof.

At the front of the shaft and at the bottom thereof is a loading platform 38 having an inner end journalled on a cross rod 39 so that said platform is vertically swingable downwardly and outwardly of the shaft into downwardly and outwardly inclined position, or, upwardly and inwardly of the shaft into a vertical out of the way position. The rod 39 is suitably fixed in a pair of posts 40 upstanding from the base 5 at opposite sides of the shaft. A cable 41 secured at one end as at 42 to the loading platform 38 and trained over a pulley 43 on one of the posts 40 provides manipulative means for swinging the loading platform 38 upwardly. A suitable cleat 44 on one of the uprights 6 is provided for winding of the cable thereon to hold the loading platform in upwardly swung position.

Returning now to the lift or cage, at the rear side thereof is an unloading platform 45 having an end hinged, as at 46, to the rear edge of the lift or cage, the arrangement being such that the unloading platform may be swung downwardly and outwardly of the lift or cage into alinement with the bottom 26 thereof, or, swung upwardly into substantially vertical position. A pair of side wings 47 on the unloading platform 45, abut the rear edges of the side walls 27 of the lift or cage when the loading platform is swung upwardly and thereby establish the vertical position of said platform. A pair of coiled springs 48 suitably connected, as at 49, to opposite sides of the unloading platform 45 and similarly connected, as at 50, to the side walls 27 of the lift or cage normally act to swing the loading platform into vertical position. A cable 41 is attached at one end to an eye bolt 52 on the rear edge of the bottom 26 of the lift or cage and is trained upwardly through a guide 53 in the unloading platform 45, said cable having a free looped end 54 adapted to be attached to a hook 55 on the bottom 26 of the cage or lift so as to retain the unloading platform 45 in vertical idle position. A cleat 56 extending across the bottom 26 of the lift or cage at the front edge of said bottom provides a chock preventing implements such as wheelbarrows from rolling off the lift or cage at the front thereof.

A pair of hand grip bars 57 may be provided at opposite sides of the shaft, one being shown in the present instance, and by means of which the structure may be wheeled from place to place as desired.

Jacks 58 are provided at opposite sides of the base 5, said jacks comprising, preferably, flat blocks pivoted at one end as at 59 to said base 5 for swinging downwardly into engagement with the ground to lift the base 5 and carriage 2 off the ground sufficiently to disengage the rollers 3 from the latter, the arrangement being such that said jacks support the entire weight of the structure and prevent shifting of the same on the rollers 3. Cranks 60 are provided on the jacks 58 for swinging the same downwardly. Normally, said jacks 58 are swung upwardly into idle position to permit the rollers 3 to sustain the weight of the structure and also to permit the structure to be rolled or shifted as desired.

Preferably, the rear of the shaft between the beam 18 and bottom of the shaft is closed against exit from the shaft by suitable cross panels 61 as shown in Figure 1.

The numeral 62 represents eye bolts for the

attachment of the cables to the carriage 1 to pull the structure into different positions and which may be provided on side edges of said carriage 1 in any desired number and location on said side edges.

Although two jacks 58 only, are illustrated in the drawings, it is to be understood that as many of such instrumentalities may be provided as is found suitable to elevate the structure off the ground.

The manner in which the described invention is used and operated will be readily understood. The structure is shoved or pulled along the ground or floor into proper relation to the floors 15 of a building construction job with the rear side of the shaft facing the floors. With the lift or cage lowered onto the bottom 6 of the shaft, and the loading platform 38 lowered to the ground or floor, the lift or cage is loaded with implements, 20 men, or materials by way of the loading platform 38. The rear bars 61 block and prevent such implements as wheelbarrows, or barrels, from rolling off the rear of the lift or cage. The lift or cage is then elevated to the desired floor level, 25 in a manner which will be obvious, and the unloading platform 45 lowered as shown in dotted lines in Figure 5, the cables 51 being first detached from the hook 55 to permit the operation. The lift or cage may then be unloaded at will. 30 In the position of the lift or cage at the second floor level, and also third floor level, the described panels 20 and bars 10 and 19 block and prevent materials or articles from rolling off the lift or cage at the front side of the shaft. When it is 35 desired to lower the lift or cage, the unloading platform 45 is raised to vertical position and retained in such position by the cables 51. The springs 48 act to swing the unloading platform 45 into vertical position but such springs are 40 constructed and arranged to be overcome by a light load on the unloading platform. The manner in which the stop yoke 12, 13, also the jacks 58 are used has already been described and need not again be entered into.

45 The foregoing, it is believed, will suffice to impart a clear understanding of my invention without further explanation.

Manifestly the invention, as described, is susceptible of modification without departing from 50 the inventive concept, and right is herein reserved to such modifications as fall within the scope of the subjoined claims.

What I claim is:

1. A portable elevator comprising a wheel supported base, a skeleton shaft forming structure arising from said base and including a front side and a rear side, a lift in said shaft, power operated means for elevating the lift to different levels corresponding to floor levels of a building, means 60 closing the front side of the structure above a level corresponding to the second floor level, means closing the rear side of the structure from the bottom of the structure from the bottom of the structure to a level corresponding to the second floor level, a loading platform pivotally mounted on said structure at the bottom and front side thereof and vertically swingable in opposite directions to lower the same to the ground and elevate the same into substantially vertical position, and manipulative means to elevate said platform comprising a cable and a pulley over which the cable is trained.

2. A portable elevator comprising a wheel supported base, a skeleton shaft forming structure arising from said base and including a front

side and a rear side, a lift in said shaft, power operated means for elevating the lift to different levels corresponding to floor levels of a building, means closing the front side of the structure above a level corresponding to the second floor level, means closing the rear side of the structure from the bottom of the structure to a level

5 corresponding to the second floor level, and a stop yoke pivotally mounted at the top of the structure for swinging into the path of the lift to prevent elevation thereof out of the top of the structure.

MARTIN M. HAIDER.
